UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TWO-WEAVE HEAD MOTION.

Application filed June 25, 1924. Serial No. 722,405.

To all whom it may concern:

Be it known that I, ELBRIDGE R. HOLMES, a citizen of the United States, residing at Worcester, in the county of Worcester and State of Massachusetts, have invented a new and useful Two-Weave Head Motion, of which the following is a specification. This invention relates to improvements in pattern mechanism for looms and more particularly to a two weave motion such as is employed for weaving buttonholes.

In such mechanisms there are usually provided two pattern surfaces and the harness levers are controlled by devices which are in contact with only one pattern surface at a time. When it is desired to change the weave the other pattern surface is brought into play and the one previously active ceases to control the harness frames.

It is the principal object of my present invention to provide a two weave motion wherein the vibrator levers have pivoted thereon members, each of which has two pattern runs and wherein the position of the pivoted member is determined by a sliding member mounted on the vibrator lever and controlled as to position by a cross rod.

Another object of my invention is to strengthen the vibrator levers by making the same of two side plates riveted together and spaced apart sufficiently to accommodate the pivoted and sliding members which effect the change of weave.

It is a still further object of my invention to provide for the removal of the pivoted and sliding members from the two part vibrator lever so that these parts may be taken out when necessary without dismantling the entire vibrator lever.

With these and other objects in view which will appear as the description proceeds, my invention resides in the combination and arrangements of parts hereinafter described and set forth in the claims.

In the accompanying drawing, wherein one form of my invention is shown,

Fig. 1 is a front elevation of a head motion having my invention applied thereto, Fig. 2 is a detailed section of a portion of the vibrator lever and the associated pattern surfaces, parts being removed to show the pivoted and sliding members more clearly,

Fig. 3 is a top plan view of the vibrator shown in Fig. 2,

Fig. 4 is a top plan view of the levers and connector which control the position of the sliding member, and

Fig. 5 is an enlarged section on line 5—5 of Fig. 2.

Referring more particularly to Fig. 1, it will be seen that I have provided loom frame 10 with an arch 11 to which is secured the frame 12 of the head. Upper and lower cylinders 13 and 14, respectively, rotate in the head and are driven by well known mechanism (not shown) so as to rotate in opposite directions. A series of harness levers, one of which is indicated at 15, is pivoted on pin 16 carried by the arches and each harness lever is provided with a connector 17 pivoted to vibrator gear 18. There is one vibrator gear for each harness lever and each gear is mounted on a vibrator lever 19 which is pivoted on heel pin 20 secured to the frame 12.

The shaft 21 on which the upper cylinder is mounted is extended to receive a pinion 22 which meshes with a gear 23 pivoted on a stud 24 fixed to the head frame. Rigid with the gear 23 is a cam 25 which is driven by the pinion and gear 23 so as to make one revolution every other pick of the loom.

As shown in Figs. 1 and 4 I have provided a connector 26, the inner end of which is slotted as at 27 to receive the extension of stud 24 to guide the connector. In order to reciprocate the connector the latter is provided with a pair of studs 28 and 29, respectively, which contact with opposite sides of the cam 25 so that as the latter rotates the connector is moved positively in both directions. Intermediate the ends of the connector there is provided a stud 30 which extends to one side of the connector 26 to pivotally support forked lever 31. The outer end of the connector 26 is provided with a slot 32 which receives the end of shaft 20. Thus it will be seen that connector 26 is reciprocated positively along a fixed line of motion and carries pivoted lever 31.

The arm 33 is pivoted on heel pin 20 and is rigid with an oscillating lever 34 having notches 35 and 36, respectively. Pivotally mounted as at 37 on an extension of the head frame is a lever 38 having a depending arm 39 by which it may be oscillated through connector 40 and having a second arm 41 which cooperates with the flattened

surface 42 formed on the lower side of lever 31. By oscillating lever 38 the lever 31 may be lowered to cause engagement between upper detent 43 and notch 35 or raised 5 as shown in the drawing to cause engagement between detent 44 and notch 36. Depending upon the position of lever 31 the lever 34 will be rocked to move arm 33 either toward or from the cylinders. Connected 10 to arm 33 is a connector 45 on which is mounted pin 46 extending across the head and placed for engagement with the sliding members to be described hereinafter.

Pattern surfaces 47 and 48, respectively, 15 are driven in opposite directions through the gears 49 and 50, respectively, which are mounted on shafts 51 and 52, respectively. The latter are driven by any appropriate mechanism (not shown) and cooperate with 20 the pivoted or oscillating member to be described hereinafter.

The matter thus far described is of the usual construction and forms no part of my present invention, being an adaptation of 25 the well known Knowles head.

My invention has more particular reference to the construction of the vibrator lever and the pivoted and sliding members carried thereby as shown in Figs. 2, 3, 4 and 30 5. As shown in Fig. 3 each vibrator is composed of a pair of side plates 60 which are riveted together at various points and spaced apart by blocks 61 at the ends respectively of the lever and studs 62. Pivotally mounted on the lower portion of each vibrator lever and limited as to angular motion by studs 62 is a chain engaging member 63 having two runs 64 and 65, respectively. Each run is shaped so as to be 35 eccentric with its corresponding pattern cylinder when in operative relationship therewith. Accordingly, surface 64 is eccentric with shaft 51 when the parts are in the position shown in Fig. 2 and when the member 63 is moved to the other position surface 65 will be eccentric with shaft 52. The chain engaging member 63 has in the central portion thereof a surface 66 concentric with stud 67 about which the member 63 moves as a pivot. The chain engaging 40 member is provided with inclined surfaces 68 and 69, respectively, which merge with plane surfaces 70 and 71, respectively.

The device for oscillating and positioning the chain engaging member 63 is shown 45 generally at 72 and comprises a sliding member having oppositely extending arms 73 and 74, respectively, and a depending central portion 75 the lower surface of which is straight and substantially parallel to the upper surfaces of arms 73 and 74. These arms have sliding contact with the lower surfaces of blocks 76 which are riveted 50 to the side members of the vibrator lever and cooperate with the arms of the slid-

ing member to hold the lower edge of the latter in contact with the concentric surface 66 of the cam 63.

The sides of the lower projection 75 are shaped and proportioned to engage the inclined surfaces 68 and 69 so that as member 72 reciprocates the member 63 will be oscillated on its pivot 67.

Under normal conditions the rod 26 will be moved to one extreme of its motion and 75 will move all of the positioning slides 72 therewith by contact with the upstanding ears 78 formed on the slides. In the position shown in Fig. 2, the oscillating members 63 will be moved so that they cooperate 80 with pattern surface 47. The parts will remain in this position until it is desired to effect a change in the weave, at which time the rod 46 will be given a motion to the right as viewed in Fig. 2, the effect of 85 which will be to bring the lower portions of all the slides in contact with surfaces 69 of the members 63, so that all of said members 63 will be oscillated to move surfaces 64 to raised position and to lower surfaces 65 into operative contact with pattern surface 48. It is to be understood that these 90 two pattern surfaces are designed so as to produce two distinct weaves.

Fig. 5 illustrates the manner of mounting 95 the chain engaging member 63 wherein it will be seen that the rivet 67 is surrounded by a bushing 77 which serves to space the side members 60 and is slightly longer than the thickness of the chain engaging member so that the latter may move thereon 100 freely without frictional contact with the sides of the vibrator.

When it is desired to remove either the 105 sliding or the chain engaging member rivet 67 will be driven out, after which the bushing 77 may be removed with the chain engaging member 63 and the sliding member may then be removed by passing the same 110 between the studs 62.

From the foregoing it will be seen that I 115 have provided a vibrator lever for use with a two weave motion constructed of two side plates between which are located positioning and pivoted members which are free to have operative movements but confined as to lateral position by the side plates. It will also be noticed that the sliding member is held in position by being at all times 120 in contact with some portion or another of the concentric surface 66, the sliding member having a rolling action with the concentric surface as well as a cam action with the inclined surfaces 68 and 69. It will further be noted that the lugs 76 and the lifting surfaces 70 and 71 of the chain engaging member are so placed with respect to the sliding member that the strain of lifting 125 the vibrator lever passes in a straight line from the chain to the bosses 76 by pass- 130

ing through the lower portion 75 of member 72.

Having thus described my invention it will be apparent that changes and modifications may be made therein by those skilled in the art without departing from the spirit and scope of the invention, and I do not wish to be limited to the details herein disclosed, but what I claim is:

- 10 1. In a pattern mechanism having a pair of pattern surfaces and a reciprocable controlling member, a vibrator lever having spaced side plates, a sliding positioner movable between the sides of the vibrator lever and having portions to engage the vibrator lever to lift the same, a pivoted member mounted on the vibrator lever and having surfaces to be engaged one at a time by the sliding positioner, said pivoted member having surfaces to engage the aforesaid pattern surfaces, and means to move the sliding member as the controller is reciprocated to oscillate the pivoted member.
- 20 2. In a pattern mechanism having a pair of pattern surfaces and a controller capable of assuming two positions, a vibrator lever formed of side plates, spaced bosses on said vibrator between the plates, a sliding positioner member reciprocable with the control member and having portions in contact in all positions thereof with the two bosses, a pattern surface engaging lever pivoted to the vibrator and having two pattern engaging surfaces to engage said pattern surfaces one at a time, means to move said pivoted member as the sliding positioner is reciprocated, and means including a portion of the pivoted member concentric with the pivot thereof to preserve contact between the sliding and the pivoted members in all positions thereof.
- 30 3. In a pattern mechanism having a pair of spaced pattern surfaces and a reciprocable controlling member, a vibrator lever extending over the pattern surfaces and having bosses thereon substantially above the centers of the pattern surfaces, a sliding positioner member in contact with said bosses and moved by said reciprocable controlling member, a pattern surface engaging member pivoted to the vibrator and having portions extending over each pattern surface,

one of said portions to be operatively positioned with respect to one of the pattern surfaces at a time only, said sliding member movable to have a portion thereof extending between one of the bosses and the pattern surface directly therebelow and in contact with that portion of the pivoted pattern surface engaging member operatively positioned with respect to the last named pattern surface.

4. In a pattern mechanism having a pair of pattern surfaces and a reciprocable controlling member, a vibrator lever having a pair of spaced bosses thereon, one boss being over one of the pattern surfaces and the other boss being over the other pattern surface, a pattern surface engaging member pivoted to the vibrator and having portions extending over each pattern surface, portions being operatively positioned with but one of the pattern surfaces at a time, and a sliding positioner member operatively related to the said controlling member to move said pattern surface engaging member on the pivot thereof, said sliding member having a portion to extend between a portion of the chain engaging member operatively positioned for one of the pattern surfaces and the boss on the vibrator over the last named pattern surface, and a surface formed on the pivoted member concentrically of the pivot thereof and in contact with a portion of said sliding member in all positions of said pivoted and sliding members.

5. A vibrator lever for two weave pattern mechanism having a pair of spaced side plates, lifting bosses carried thereby, a pattern surface engaging member pivoted thereto and having a pair of oppositely extending pattern surface engaging arms, a sliding positioner member having two operative points of contact with the pattern surface engaging member, and a surface formed on the pivoted pattern surface engaging member concentric with the pivot thereof and in contact with a portion of the sliding member in all positions of said sliding and pivoted members.

In testimony whereof I have hereunto affixed my signature.

ELBRIDGE R. HOLMES.
